CLAIM

(**) Term: **14 Years**

The ornamental design for a digital sound relaxation and sleep-inducing system, as shown and described.

(21) Appl. No.: **29/093,975**

DESCRIPTION

(22) Filed: **Sep. 23, 1998**

FIG. 1 is a front view of the digital sound relaxation and sleep-inducing system of the present invention;

(51) LOC (7) Cl. **10-05**

FIG. 2 is a rear view of the digital sound relaxation and sleep-inducing system of the present invention;

(52) U.S. Cl. **D10/116**

FIG. 3 is a top view of the digital sound relaxation and sleep-inducing system of the present invention;

(58) Field of Search D24/188; D10/116;

FIG. 4 is a bottom view of the digital sound relaxation and sleep-inducing system of the present invention;

D14/156; 381/61, 62, 63; 340/825.25, 825.24;

FIG. 5 is a right side view of the digital sound relaxation and sleep-inducing system of the present invention; and,

607/141, 72, 64, 54; 600/27, 26; 601/90,

FIG. 6 is a left side view of the digital sound relaxation and sleep-inducing system of the present invention.
